UNITED STATES PATENT OFFICE.

JOSEPH O. BEAZLEY, OF BALTIMORE, MARYLAND.

FAUCET.

No. 809,895.

Specification of Letters Patent.

Patented Jan. 9, 1906.

Continuation of application Serial No. 175,199, filed September 30, 1903. This application filed March 30, 1905. Serial No. 252,911.

To all whom it may concern:

Be known that I, JOSEPH O. BEAZLEY, a citizen of the United States, residing in the city of Baltimore and State of Maryland, have invented a new and useful Faucet, of which the following is a specification.

The invention relates to improvements in faucets.

The object of the present invention is to improve the construction of faucets and to provide a simple and comparatively inexpensive one of great strength and durability designed for use on coolers and supply-pipes and in various other places where an ordinary faucet may be employed and adapted to close automatically when released without the use of springs and without depending upon the pressure of the water or other fluid.

A further object of the invention is to provide an automatically-closing faucet of this character in which the means for closing the valve will be cushioned by the latter.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective view of a faucet constructed in accordance with this invention, the weighted operating-arm being shown elevated in full lines and dropped in dotted lines. Fig. 2 is a longitudinal sectional view of the same, the valve being open. Fig. 3 is a transverse sectional view. Fig. 4 is a detail view of the valve and the actuating means. Fig. 5 is an end view. Fig. 6 is a perspective view illustrating another form of the invention in which the weighted operating-arm swings upwardly from a vertical to a horizontal position. Fig. 7 is a vertical longitudinal sectional view of the same. Fig. 8 is a transverse sectional view. Fig. 9 is a horizontal sectional view taken substantially on the line 9-9 of Fig. 8. Fig. 10 is a detail perspective view of the stop-collar. Fig. 11 is a detail view of the valve-stem. Fig. 12 is a detail sectional view illustrating the construction

of interiorly-arranged stops for limiting the movement of the weighted operating-arm.

Like numerals of reference designate corresponding parts in all the figures of the drawings.

1 designates the body of the faucet, which is provided with a discharge spout or end 2 and which may be constructed of any suitable material, as will be readily apparent. The body of the faucet (shown in Figs. 1 to 3, 65 inclusive) is horizontal; but when the valve mechanism is employed in connection with the flushing-tank or analogous structure it may be arranged either in a horizontal or vertical position. The body of the faucet has an enlarged intermediate portion 3, and it is provided at its rear end with a cylindrical extension 4, forming a valve-chamber and presenting smooth inner walls for guiding a valve 5, as hereinafter explained, to a seat 6^a, which is formed at the front or inner end of the extension 4, as clearly shown in Fig. 2 of the drawings. The extension 4 is exteriorly threaded to receive a cap 7, which is provided with a threaded aperture 8 for the reception of a pipe-section 9, but the cap may be provided with any other suitable means for enabling the faucet to be mounted in the position in which it is to be used. The valve preferably consists of a semispherical metal cap 10 and an elastic ball-shaped body portion 11. The cap is provided with an annular series of longitudinal guiding-arms 12, which fit snugly within the cylindrical valve-chamber and which guide the valve to and from its seat, whereby it is properly seated and closed. These guiding-arms also prevent the valve from accidentally twisting or binding, and thereby interfering with the operation of the means for automatically closing it. The elastic body portion may be constructed of rubber or any other suitable material, and the two parts are connected by a stem 13, having a bifurcated front end and threaded at its rear portion for the reception of a nut 14. The front bifurcated end of the stem is enlarged to form an engaging shoulder, and it receives one end of a link 15, which is provided at its other end with a collar 16. The inner end of the link 15 is connected with the bifurcated end of the stem by a suitable pivot 17, and the collar 16 receives a cam 18 of a shaft 19, whereby when the shaft is rotated the valve will be moved inward and outward. The cam consists of an eccentrically-mount-

ed circular head formed integral with the shaft, which has an inner conical or tapered end 20 to fit a conical bearing 21 of the faucet body or barrel. The faucet body or barrel is 5 extended laterally at one side of the enlarged portion to form the bearing 21, and in order to equalize the friction or strain and prevent the operating mechanism from binding or interfering with the automatic closing of the 10 valve the said body or barrel is provided with an opposite bearing 22, and it has an opening of sufficient size to permit the introduction and removal of the cam. The faucet is provided at the lateral aperture with an upwardly-extending threaded flange 23, forming a packing-chamber or stuffing-box and adapted to receive a suitable packing 24. The shaft is provided with a collar 25 to fit the bearing of the adjacent side of the faucet, 15 and this collar, which is circumferentially recessed to provide a peripheral flange, may be either fixed or loose on the shaft, as desired. The peripheral flange overlaps the bearing portion of the faucet body or barrel, and the 20 recessed portion of the collar fits into the same, as clearly shown in Fig. 3. By this construction the cam-shaft is journaled at each side of the body or barrel of the faucet and there is no liability of the parts binding and 25 accidentally interfering with the operation of the automatically-closing valve. The laterally-extending flange 23 receives a cap 26, which is interiorly threaded and which is provided with a central opening for the shaft, 30 and the latter has a polygonal portion 27 for the reception of a weighted arm 28. The weighted arm 28 is provided at one end with an opening to fit the polygonal portion of the cam-shaft, and the terminal of the latter is 35 threaded for a nut 29, which retains the weighted arm on the shaft. The weighted arm, which extends upward at an inclination when the valve is open, is angularly bent at 40 30 and 31 to arrange its upper portion contiguous to the body or barrel of the faucet and its intermediate portion extends over the cap 26, as clearly shown in Fig. 1 of the drawings. The upper end of the valve-actuating arm 28 is provided with an enlargement or 45 50 weight, which may be in the form shown, but which may be shaped into a grip or handle to facilitate its operation. The valve-actuating arm is swung upward to open the valve, and the weight on said arm operates to close 55 the latter automatically as soon as the actuating-arm is released. The oscillating actuating-arm is limited by laterally-projecting front and rear lugs 33, which prevent the said arm from being forced too far in either direction, and breakage of the parts is thereby 60 prevented. These lugs are cast integral with the body of the faucet, but any other suitable stop may be provided for this purpose.

In Figs. 6 to 11, inclusive, of the drawings 65 is illustrated another form of invention in

which a valve 34 is movable in a vertical direction instead of horizontally. The body 35 of the faucet, which is disposed vertically, has a horizontal discharge-spout 36 and is provided with an enlarged intermediate portion 37. The lower end 38 of the body is threaded for the reception of an extension or section 39, which constitutes a valve-chamber and which is provided with means for mounting the faucet in position. The lower 70 edge 40 of the body forms a valve-seat and is arranged at one end of the valve-chamber of the extension, which is screwed against a projecting flange 41. The valve is constructed substantially the same as that heretofore described, being composed of an elastic body of a metal cap 42, fitting on the rear end of the valve. The valve is provided with a stem 43, which pierces the valve-body and the cap and which is threaded at the lower end to receive a nut 44, a washer being interposed between the nut and the cap. A suitable stop or shoulder 45 is arranged at an intermediate point on the stem for engaging the upper end of the elastic weight of the valve. The 80 upper end of the valve-stem is provided with an integral eye or collar 46, which is arranged on a crank 47 of a shaft 48. The valve-stem is also provided at an intermediate point with radial wings 49, which assist in centering the valve and which are adapted to reduce the vibration and jar of the same in opening and closing. The body or barrel 35 of the faucet is provided with a lateral aperture having an outwardly-extending flange 100 50, forming a packing-chamber or stuffing-box and adapted to receive a packing 51, preferably consisting of rings of compressed sponge or felt, which when moist are adapted to expand and effectually prevent any leakage of the faucet through the lateral opening. The threaded flange receives a cap 52, which is provided with an opening for the crank-shaft, and the latter has a central enlargement 53, arranged within the threaded flange and engaging an interior shoulder thereof, as clearly shown in Fig. 8 of the drawings. The packing is interposed between the enlargement 53 and the cap, suitable washers 54 and 55 being preferably arranged at the inner and outer faces of the packing. The outer end of the crank-shaft is square to receive a weighted valve-actuated arm 56. The weighted arm is arranged in a vertical position when the valve is closed, 110 and it is adapted to swing upward therefrom to open the valve, the amount of swing or the distance the weighted arm is swung corresponding to the opening movement of the valve. The valve may be arranged to open 115 120 to any desired extent, and the valve-stem and the crank are proportioned, so that the valve will be securely seated when the upwardly-swinging arm returns to its vertical position. The weighted arm may be ar- 125 130

ranged in any other desired position that will effect an automatic closing movement of the valve, and its movement is limited by stops 57 and 58, which are arranged in the path of 5 a projecting portion or pin 59 of the weighted arm. The stops are formed integral with a collar or ring which is secured on the extension of the faucet body or barrel by means of a clamping-screw 60 or other suitable means. 10 The stops may be disposed in any position which will cause the weighted operating-arm to swing downward by gravity to close the valve, and they also may be arranged interiorly of the faucet, as well as exteriorly 15 thereof. In Fig. 12 of the drawings is illustrated one form of interiorly-arranged stops. These stops 61 and 62 are formed by an arcuate recess in the outwardly-extending tubular portion or flange 50 and are engaged by 20 a pin 63, mounted on and projecting from the shaft. The lower stop is vertical, and the upper stop is arranged at an inclination and at a point slightly above the horizontal, the swing of the weighted arm being preferably 25 slightly in excess of one-fourth of a revolution, but the throw of the arm may be varied to secure the desired opening movement of the valve, as will be readily understood. Any other internal arrangement of stops may 30 be employed for limiting the swing of the weighted operating-arm.

Having thus fully described my invention, what I claim as new, and desire to secure by Letters Patent, is—

35 1. In a device of the class described, the combination of a body having a valve-seat, a

valve arranged to engage the seat at the pressure side thereof, a horizontal shaft mounted on the body at the opposite side of the valve-seat and connected with the valve, an upwardly-extending weighted arm connected with the shaft at one end and arranged at an inclination when the valve is open, whereby it is adapted to close the valve automatically, and stops arranged on the body in the path 40 of the arm for limiting the movement thereof in opening and closing.

2. In a device of the class described, the combination of a body having a seat, a valve arranged to engage the seat at the pressure 45 side thereof, a horizontal shaft mounted on the body at the opposite side of the valve-seat and connected with the valve, a weighted arm connected with the shaft and arranged to swing upwardly to open the valve and 50 movable downwardly automatically by its own weight to close the same, the extent of movement of the valve corresponding with the movement of the weighted arm, whereby the valve will be properly seated 55 when the arm is at the limit of its downward movement, and stops for limiting the movement of the weighted arm in opening and closing the valve.

In testimony that I claim the foregoing as 60 my own I have hereto affixed my signature in the presence of two witnesses.

JOSEPH O. BEAZLEY.
